UNITED STATES PATENT OFFICE.

JERE L. WENTZ, OF PASSAIC, NEW JERSEY.

DETACHABLE RIM AND WHEEL.

Application filed September 22, 1925. Serial No. 57,826.

My invention relates to an improvement in detachable rims and more particularly to such rims for tractor wheels.

An object of my invention is to provide a rim of simple construction. Another object is to avoid the necessity of piercing the wheel body in order to fasten the rim on the body. A still further object is to provide a positive, non-slippable and easily removable locking means.

The preferred form of my invention is illustrated in the accompanying drawings in which

Fig. 1 is a side view of the wheel;

Fig. 2 is a cross section of the felloe, rim and lugs;

Fig. 3 is a perspective view of the lug; and

Fig. 4 is a perspective view of a modification of the lug.

Similar characters of reference refer to similar parts throughout the several views.

The type of wheel with which my detachable rim is to be used is shown at 1, having the rim attached thereto. The fixed rim of the wheel 1 having the hub 2 is composed of two annular angle irons 1' riveted together flange to flange by the rivets 4. These rivets also serve to fasten the spokes 3 to the angle irons between the flanges of the same as shown in Fig. 2.

My invention is applied to a wheel such as is above described, and includes a circular metal band or annulus 6 having holes drilled therethru near the outer edge along the periphery on either side. The circular band may be formed from a flat sheet of malleable metal or may be cast or made in any other well known and desired manner. The holes drilled in said band are at points corresponding to the interval between respective spokes or between every other spoke or as desired in the wheel 1. The holes are preferably countersunk to receive screw heads.

Lugs 7 and 7' are provided as shown in Figs. 3 and 4. That in Fig. 3 has a vertical threaded hole 8 at substantially the middle of its top side. The inside face 10 has two cup shaped socket holes 11 therein, spaced, and of a size, to fit over the rivet heads 4. The lug 7' has the threaded screw hole 8' as provided for the lug 7. Instead of the sockets 11 this modification has on its face 10' a vertical rib 11' which extends the full height of the lug.

My invention is assembled and attached

to the wheel 1 in the following manner. The circular band 6 is slid on over the wheel 1 until the mid point of the band is in the longitudinal center line of the wheel and with the peripheral holes in the plane of the center lines of the spokes and the axis of the wheel so that one rivet of each pair will lie on either side of the hole.

Lugs 7 or 7' as desired are then placed either with the sockets 11 of the lug 7 over the rivet heads and the hole 8 in line with the hole in the band or with the rib 11' of the lug 7' between the rivets of each pair. This is done on either side of the flange at a spoke and preferably at every other spoke as shown in Fig. 2. As each lug has the hole 8 aligned with the hole in the band a flat headed screw 9 is inserted and driven flush with the outside surface of the band. When these lugs have been so fastened to the band or detachable rim by the screw 9 it will be evident that the rim is locked against peripheral slip due to the sockets 11 or ribs 11' and that the lugs on either side also prevent any lateral displacement. Therefore the rim is securely but detachably held in fixed position.

Having thus described my invention I claim—

1. In a device of the character described the combination of a wheel having a felloe including two annular angle irons flange to flange, rivets fastening said angle irons together, heads on said rivets projecting from said flanges, an annular band on the felloe, a plurality of lugs on either side of said flanges, said lugs abutting said flanges and said band, means on said lugs to engage the projecting heads of the rivets and screws binding the lugs to the band.

2. In a tractor wheel the combination of two annular angle irons, rivets fastening said angle irons flange to flange to form a tread of inverted T-shaped cross section, the heads of said rivets projecting from said flanges, a one piece circular band surrounding said tread, lugs on either side of said tread, means on said lugs to engage said rivet heads and means to lock said lugs to said band whereby the band is locked to said tread.

In testimony whereof, I have signed my name to this specification this 14th day of Sept., 1925.

JERE L. WENTZ.
